UNITED STATES PATENT OFFICE.

IRVING F. NILES, OF PLAINFIELD, NEW JERSEY, ASSIGNOR TO R. HOE AND CO., OF NEW YORK, N. Y., A CORPORATION OF NEW YORK.

TRANSFER-PRESS.

1,193,046.

Specification of Letters Patent.

Patented Aug. 1, 1916.

Application filed December 4, 1913. Serial No. 804,593.

To all whom it may concern:

Be it known that I, IRVING F. NILES, a citizen of the United States, residing at Plainfield, county of Union, and State of New Jersey, have invented certain new and useful Improvements in Transfer-Presses, fully described and represented in the following specification and the accompanying drawings, forming a part of the same.

This invention relates to certain improvements in transfer presses, in which there are employed a transfer roll or cylinder provided with a suitable transfer surface, a plate supporting bed, and a work supporting bed, the transfer cylinder passing successively over these beds to take up a design from the plate and transfer it to the work, the machine being so constructed that the cylinder is out of contact with the beds on its return or non-impression stroke. This type of press is particularly adapted for printing on heavy substances, as metal, glass and the like, but it may be employed, if desired, for printing on paper, it being especially useful when used in such capacity for taking proofs of work which is to be printed from a stone or like printing surface. With presses of this type, however, when used for printing on paper, difficulty has been found in keeping the work in proper position on the work supporting bed while the design is being transferred to it.

It is the especial object of the invention to provide a means for securely positioning the work on the bed during impression, these means being preferably of such character that they will be operated to secure and release the work by the movement of the cylinder.

It is a further object of the invention to provide an improved construction by which the cylinder will be caused to clear the beds during its return or non-impression stroke.

With these and other objects not specifically referred to in view, the invention resides in certain constructions and parts which will be fully described in connection with the accompanying drawings, in which—

Figure 1 is a side elevation of a transfer press embodying the improvements, certain parts being broken away; Fig. 2 is a longi-

tudinal section of the construction shown in Fig. 1, the transfer cylinder being omitted; Fig. 3 is an end elevation of the construction shown in Fig. 1, certain parts being broken away and certain parts being shown in section, the view showing the cylinder in the position it assumes when on its impression stroke; Fig. 4 is a similar view of one side of the machine partly broken away and partly in section, showing the parts in the positions assumed when the cylinder is on its return or non-impression stroke and has been lifted so as to clear the bed; and Fig. 5 is a detached fragmentary plan view of the gripper mechanism for holding the work in position on the bed of the machine.

Referring now to the drawings, a machine constructed in accordance with the invention will include a transfer cylinder 1. This transfer cylinder in the particular machine illustrated is arranged to be operated by hand, and is provided on either side with a suitable hand wheel 2 by which the cylinder may be reciprocated over the beds. This cylinder 1 is provided with the usual transfer surface, which may be a blanket 3, suitably secured to the cylinder, and capable of having its tension on the cylinder adjusted by means of a usual tension roll 4.

The cylinder 1 is reciprocated successively over a plate-supporting bed 5 and a work-supporting bed 6, which are supported in the frame of the machine so as to be capable of vertical adjustment to accommodate plates or stones of various thicknesses and different kinds of work. The means for supporting the beds and for effecting this adjustment may be somewhat varied, but in the particular construction illustrated there are provided cross frames 7, 8, at each end of the machine, and a cross frame 9 in the central portion thereof, these frames being supported on projections 10 secured on the frame of the machine. The beds are provided with ears 11 through which are threaded bolts 12, these bolts resting on the flanges of the cross frames. The beds are thus supported by these bolts, and by adjusting the bolts the beds may be raised and lowered as desired. The plate supporting bed is shown as supporting a stone 14,

though it will be understood that any other type of printing surface may be supported on the bed if desired or necessary.

Machines constructed in accordance with 5 the invention will be provided with means whereby the cylinder and the beds may be caused to clear on the return or non-impression stroke of the cylinder, and these means, in the best constructions, will act to lift the 10 cylinder sufficiently to enable it to clear the beds. These cylinder lifting means will, furthermore, in machines embodying the invention in its best form, be arranged so as to be operated either by the press operator 15 or automatically by the movement of the cylinder. While these means may be varied, in the best constructions and as illustrated the cylinder is provided at each of its ends with pinions 15 which mesh with 20 racks 16 suitably secured as by bolts 17 to the side frame 18 of the machine, these racks being, as illustrated, located outside the side frames. While two pinions 15 and two racks 16 have been illustrated, it will 25 be understood that if desired one of these pinions and the corresponding rack may be omitted. Inside the racks the cylinder is provided with a bearing surface 19 which, when the cylinder is on impression stroke, 30 is adapted to run on the top edge of the side frames 18, as shown in Fig. 3, the cylinder when in this position being in printing relation with the beds. For lifting the cylinder so as to clear the beds, on its return or non- 35 impression stroke, there are provided a pair of lifter bars 20 which are located between the side frames 18 and the racks 16, the securing bolts 17 passing through the bars which are suitably slotted, as shown at 21, 40 to permit their lifting movement. The top edges of these lifter bars, when in their lowermost position, are preferably of the same height as the top edges of the frames 18 and contact with the outer portion of 45 the bearing surface 19 of the cylinder when the cylinder is on its impression stroke. On the return stroke, the lifter bars are operated to raise or lift the cylinder to clear the beds, the cylinder when thus lifted being 50 clear of the side frames and the rack and running during its return stroke on these lifter bars, the means employed for lifting these bars being of such character as to firmly hold the bars in raised position and 55 form a track for the cylinder to run on on its return stroke. The means for raising these lifter bars may be of somewhat varied character, but they will be of such construction preferably that they may be operated 60 either by the press operator or automatically by the movement of the cylinder. In the construction illustrated, there is provided a pair of crank arms 22, 23, pivoted on suitable studs 24 in the frame of the ma-

chine. These crank arms are connected at 65 one end by a bar 25 secured thereto and at their other ends connect through links 26 and arms 27 with operating fingers 28 pivoted at 29 in the frame of the machine. These crank arms are provided with notched 70 or recessed portions in which seat pins 30, the other ends of these pins taking into suitable notches in the underside of the lifter bar 20 before referred to. This arrangement of cranks and pins is duplicated on the 75 other side of the machine and forms in effect a number of toggles which when straightened out operate to raise the lifter bars and hold the same firmly in elevated or raised position until the toggles are broken, thus 80 forming a firm track for the cylinder to travel on on its return or non-impression stroke.

In the operation of the construction so far described the operating fingers 28 are 85 arranged to be in the path of the bearing surfaces 19 of the cylinder before referred to, and are struck by the cylinder at each end of its traverse over the bed, the cylinder thus automatically operating the lifter bars 90 to cause them to lift the cylinder clear of the beds at the end of the impression stroke, and at the end of the return or non-impression stroke the cylinder likewise acts through the other operating finger to break 95 the toggle, thus causing the lifter bars to be depressed and the cylinder brought into printing relation with the beds.

It may be desirable in some instances to operate the lifter bars by means operable 100 by the pressman, and one such means is provided by the invention. In the particular construction illustrated there is provided another crank 31 pivoted at 32 in the frame of the machine, one arm of which is 105 connected to the bar 25 before referred to, the other arm of which is connected to a link 33 pivoted on a stud 34 carried on a foot treadle 35 pivoted on a rock shaft 36 suitably journaled in the frame of the ma- 110 chine. The crank 31 may be, like the cranks 22, 23, before referred to, notched or recessed to take one end of a pin 37, the other end of which seats in a notch in the underside of the lifter bar. This construction is 115 duplicated on the other side of the machine, and through it the operator may raise and lower the lifter bars from either side of the machine. If desired, other arms may be provided, such as arm 38, connected to rod 120 25, before referred to, and recessed to take pin 39, this pin taking into a recess in the underside of the lifter bar, this construction also being duplicated on the other side of the machine.

It will be seen from the construction so far described that there is a firm support or track provided for the cylinder to run

on during its return or non-impression stroke. Furthermore, by the arrangement shown in which the racks are located outside the lifter bars, these racks are readily accessible and may be readily gotten at to be cleaned.

To prevent endwise displacement of the cylinder and to keep it in position during its return stroke there may be provided on 10 the cylinder holding flanges 40, these holding flanges being adapted to bear against the side frames 18 of the machine, as shown in Figs. 3 and 4.

Machines constructed in accordance with 15 the invention will be provided with means for holding the work firmly in position while it is receiving the impression from the transfer cylinder. These positioning means may be of varying character, but in the best 20 constructions will be caused to seize or release the work by the movement of the cylinder. In the construction illustrated, these holding means are grippers 41 carried on a shaft 42 extending across the machine. 25 While two gripper fingers have been shown, it will be understood that as many as desired may be employed. These grippers are arranged to be actuated to seize the work after it has been positioned on the bed and 30 after the cylinder has passed the bed on its return or non-impression stroke and to release the work after the cylinder has completed its printing or impression. These means may be varied, but in the construction 35 illustrated may be effected through the operating fingers 28 before referred to. In the particular construction illustrated, the shaft 42 on which the gripper fingers are carried is supported in ears 43 secured by 40 suitable bolts 44 to a cross bar 45 supported in the cross frame 9, before referred to. The bar 42 is rocked to move the grippers in holding and releasing positions through an arm 46 and link 47 connected to an arm 45 45 on the rock shaft 36, before referred to, a spring 49 being provided, if desired, to effect a yielding movement of the parts. With this construction it will be seen that when the cylinder has finished its return 50 stroke and has moved the operating finger 28 at the left-hand end of the machine, the movement of this finger through bar 25, arm 31, link 33 and treadle 35 has rocked the rock shaft 36 and caused the grippers 55 to seize the work which has been placed on the work bed. At the end of the impression stroke, the cylinder, contacting with the operating finger 28 at the other end of the machine, through these connections causes 60 the grippers to release their hold on the work. It will also be seen that by the construction described, the grippers may be also operated by the foot treadle.

While the invention has been shown and

described in its preferred form, it will be understood that various changes in the construction and arrangement of the various devices employed may be made without departing from the invention, and it is understood that such changes and variations may be made.

What is claimed is:

1. In a transfer press, the combination with a transfer cylinder, of a plate supporting bed and a work supporting bed over 75 which the cylinder travels successively, means for causing the cylinder and beds to be moved out of contact with each other when the cylinder is traveling in one direction, and work holding devices operatively 80 connected with said means for holding the work in position on the work supporting bed while the cylinder is operating on the work and releasing the work during the action of the cylinder. 85

2. In a transfer press, the combination with a transfer cylinder, of a plate supporting bed and a work supporting bed over which the cylinder travels successively, 90 means for causing the cylinder and beds to be moved out of contact with each other when the cylinder is traveling in one direction, and means brought into operative position by the cylinder for holding the work on the work supporting bed while the 95 cylinder is operating on the work.

3. In a transfer press, the combination with a transfer cylinder, of a plate supporting bed and a work supporting bed over which the cylinder travels successively, 100 means for causing the cylinder and beds to be moved out of contact with each other when the cylinder is traveling in one direction, means for holding the work in position on the work supporting bed while the 105 cylinder is operating on the work, and means operated by the cylinder for causing the holding means to seize and release the work.

4. In a transfer press, the combination 110 with a transfer cylinder, of a plate supporting bed and a work supporting bed over which the cylinder travels successively, means for causing the cylinder and beds to be moved out of contact with each other 115 when the cylinder is traveling in one direction, grippers for holding the work in position on the work supporting bed while the cylinder is operating on the work, and means operated by the cylinder for causing 120 the grippers to seize and release the work.

5. In a transfer press, the combination with a transfer cylinder, of a plate supporting bed and a work supporting bed over which the cylinder travels successively, 125 means for causing the cylinder and beds to be moved out of contact with each other when the cylinder is traveling in one direc-

tion, grippers for holding the work in position on the work supporting bed, a rock shaft for operating the grippers, fingers at each end of the machine with which the cylinder contacts, and connections between the fingers and the rock shaft for rocking the latter to cause the grippers to seize and release the work.

In testimony whereof, I have hereunto set my hand, in the presence of two subscribing witnesses.

IRVING F. NILES.
